UNITED STATES PATENT OFFICE.

SAMUEL COHN, OF NEW YORK, N. Y.

DESIGN FOR A LABEL-BLANK.

40,531.

Specification for Design.

Patented Feb. 22, 1910.

Application filed December 23, 1909. Serial No. 534,741. Term of patent 7 years.

To all whom it may concern:

Be it known that I, SAMUEL COHN, a citizen of the United States, residing at the city of New York, borough of Manhattan, in the county and State of New York, have invented a new, original, and ornamental Design for Label-Blanks, of which the following is a specification, reference being had to the accompanying drawing, forming part thereof, in which is shown a face view of a label blank incorporating my said design.

In said drawing the label blank is shown as of rectangular outline having a plain border. The body portion of said label blank within said border is surrounded by an irregular fretted border or frame. At the central portion of said blank, adjacent to the upper edge thereof, is displayed an

irregular shield-shaped ornament upon which a wreath is superposed which partly incloses an eagle passant. Sprays of grain extend from below the lower central portion of the shield-shaped ornament, pass under the same, and have their upper ends projecting from either side of said ornament. Across the central portion of the label blank is horizontally arranged an ornamental, longitudinal scroll or band of irregular outline.

I claim—

The ornamental design for a label blank, as herein shown and described.

SAMUEL COHN.
